UNITED STATES PATENT OFFICE.

EDWARD W. HIRSCHMAN, OF FINDLAY, OHIO.

EGGSHELL CRUSHER AND PULVERIZER.

Application filed July 3, 1924. Serial No. 724,099.

To all whom it may concern:

Be it known that I, EDWARD W. HIRSCHMAN, a citizen of the United States, residing at Findlay, Ohio, in the county of Hancock and State of Ohio, have invented certain new and useful Improvements in Eggshell Crushers and Pulverizers, of which the following is a specification.

This invention relates to a pulverizer and crusher of novel design and construction intended for household use and particularly to a device for pulverizing and crushing egg shells preparatory to the mixing of same with salt for incorporating in food stuffs.

That the American diet is deficient in lime contents is well recognized and it has been proposed to remedy this defect by mixing egg shells with salt and using the mixture in a salt cellar for the value of the lime contents of the shell. An obstacle to the practicable adoption of this suggestion is the lack of a suitable apparatus for crushing and pulverizing the egg shells so that they may be reduced to a fine powder suitable for use in the manner prescribed and it is one of the special objects of the present invention to eliminate this difficulty by providing an inexpensive, hand-operated, and serviceable apparatus by which the crushing and pulverizing of egg shells can be quickly and efficiently accomplished.

Other objects and advantages of the invention may be apparent from the following description, taken in connection with the accompanying drawings illustrating the practical embodiment of the invention, and wherein:

Figure 1 is an end view, partly in elevation and partly in section, of one type of device contemplated by the invention.

Figure 2 a sectional view thereof taken on line 2—2 of Figure 1.

Figure 3 is a detailed view, in perspective, of one of the combined end disks and covers of the device.

Figure 4 is a view of another type of device contemplated by the invention.

Figure 5 is a sectional view thereof taken on line 5—5 of Figure 4.

Figure 6 is a detailed view, in perspective, of the pulverizing disk used with the device shown in Figure 4, and:

Figure 7 is a sectional view of a further variation in the construction and design of the invention, the device being viewed from the rear.

As will be apparent from Figures 1 to 3 inclusive, the device may consist of a cylindrical housing 10 having end-covers 11 attached to provide a crushing chamber where-in are two revolving hammers 12 which operate on opposite sides of a single break-down bar 13. The inlet 14 to the crushing chamber is at the top of the housing and is provided with a slide closure 15. The entire device may be fastened to a support by means of a clamp at the bottom of the housing and consisting of a thumb screw 16 adjustable with respect to the clamp jaw 17. The end-covers 11, as well as the break-down bar 13, are fastened to the housing in any suitable manner so as to be readily removable for disassembling the device or for replacement of the parts.

The hammers 12 are mounted on the square portion of a shaft 18 and revolve with the shaft, being normally pressed apart and forced against pulverizing disks 19 by means of an expanding spring 20 encircling the shaft between the hammers. Each end-cover 11 carries one of the two pulverizing disks 19; the disk and cover being in one piece, as shown in Figure 3, and the face of each disk, which is of smaller diameter than the cover so as to extend within the crushing chamber, is provided with a plurality of radially disposed grooves 21. The construction of the hammers is such that the blades 22 thereof project outwardly from a common center somewhat like the spokes of a wheel but are set at an angle, preferably 30 degrees, inclined in the direction of the pulverizing disk against which the hammer is pressed.

The purpose and object of having the blades inclined is to obtain a "shearing effect" as each blade moves past a groove of the disk. That is to say, as the blades pass the grooves or corrugations, they strike them at an angle and cut like a pair of scissors. The shaft 18, on which the hammers are mounted, has its ends rounded and supported in suitable bearings 23 of the end-covers and the entire assembly of hammers 12, spring

20, and shaft 18, is revolved by a hand crank 24 which is screwed onto the threaded extension of the shaft.

In using the device, the egg shells are fed, 5 a little at a time, into a crushing chamber through the inlet and are first crushed between the break-down bar and the blades of the revolving hammers, being thus broken up into small particles or flakes. These 10 small particles or flakes, being constantly agitated and whirled about between the inclined blades, are thereby ultimately propelled against the pulverizing disk, to be caught and held by the grooves of the latter, and subsequently ground to powder or 15 dust. The blades of the hammers thus serve to break up the shell during the "flaking operation" and also co-operate with the grooved disks in pulverizing the flakes. The operation is continued until the product is as fine 20 as desired and it is then poured out of the inlet.

In Figures 4 to 6 inclusive, is shown a modification of the invention wherein only 25 a single pulverizing disk is required. This disk, indicated at 26, is centered within the crushing chamber and is secured to the housing by means of suitable fasteners 27. Both 30 sides of the disk are corrugated and present a series of radially disposed ratchet-like 35 projections 28 upon which the "flakes" of the crushed egg shells are adapted to collect. A pair of hammers 29, corresponding to hammers 12 previously described, are provided 40 one on each side of the disk and two break-down bars 30 are also used, there being one bar disposed adjacent the lower outside edge of each hammer and secured to cover 31 by suitable fasteners 32. A separate 45 spring 33 is associated with each hammer, each spring being confined between a hammer and an end-cover 31 of the housing. In all other respects, the device corresponds with the one previously described and the operation is the same.

Figure 7 illustrates a modification which combines the structural features of the two preceding designs and indicates how this may be accomplished to produce a machine 50 of larger size and greater capacity.

Having thus described the invention, what I claim as new and desire to protect by Letters Patent, is:

What is claimed is:

55 1. An egg-shell crusher and pulverizer including a crushing chamber, crushing means therein including a pair of revolving hammers and a stationary break-down bar between which the shell is adapted to be 60 broken up into flakes during revolution of the hammers, a pulverizing member for each hammer presenting a corrugated surface over which the blades of the hammers are adapted to move, the corrugations of the 65 member serving to catch and hold the flakes

of the shell propelled thereagainst by the blades of the revolving hammer and the said blades being inclined to strike the grooves at an angle to obtain a shearing cut, and elastic means tending to force the said hammers against the said corrugated surfaces of the said pulverizing members. 70

2. An egg-shell crusher and pulverizer comprising a cylindrical housing having end-covers presenting grooved surfaces, a 75 break-down bar within the housing, a pair of revolving hammers operating on opposite sides of the said bar, and elastic means normally holding the said hammers apart and forcing them against the said grooved surfaces of the said end-covers. 80

3. An egg-shell crusher and pulverizer including a cylindrical housing having a peripheral inlet, removable end-covers closing opposite sides of the said housing and presenting grooved surfaces, a break-down bar within the housing, a pair of revolving hammers operating on opposite sides of the said bar, a shaft having its ends journaled in the 90 said end-covers and having the said hammers mounted thereon to turn therewith, a crank for turning the shaft, and elastic means normally holding the said hammers apart and pressed against the said grooved surfaces of the end-covers. 95

4. An egg-shell crusher and pulverizer including a cylindrical housing with an outlet at the top and a clamp integral with the bottom, removable end-covers closing opposite sides of the housing and presenting grooved surfaces, a shaft having its ends journaled in the said end-covers and having the portion between its ends squared, a break-down bar within the housing, a pair of hammers mounted on the squared portion of the shaft and operating on opposite sides of the said bar, means for normally forcing the said hammers against the grooved surfaces of the said end-covers, and means for turning the shaft. 100 105

5. An egg-shell crusher and pulverizer including a crushing chamber, end-covers closing opposite sides of the chamber and presenting radially grooved surfaces, a break-down bar within the chamber, a pair of revolving hammers operating on opposite sides of the said bar, and means for holding the said hammers apart and pressed against adjacent grooved surfaces of the said end-covers, said hammers being provided with radially extending blades inclined in the direction of the grooved surfaces against which pressed. 110 115

6. An egg shell crusher and pulverizer comprising a cylindrical crushing chamber, a hammer revolvably mounted within the said chamber and presenting radially disposed blades, a stationary bar extending horizontally of the said chamber in parallelism to the side walls thereof and positioned 120 125 130

immediately adjacent to one side of the said hammer for co-operation with the blades of the latter in breaking the shell into flakes, and a stationary disk adjacent to the opposite side of the hammer and presenting corrugated surfaces for co-operation with the sides of the blades in pulverizing the flakes, the blades of the said hammer having surfaces inclined in the direction of the pulverizing disk for the dual purpose of conducting the flakes to the grooves of the said disk and to obtain a shearing effect as each blade moves past a groove of the disk. 10

In testimony whereof I affix my signature.

EDWARD W. HIRSCHMAN.
